DESIGN FOR A CAKE OR FRUIT DISH.

SPECIFICATION forming part of Design No. 14,525, dated December 25, 1883.

Application filed November 7, 1883. Term of patent 7 years.

To all whom it may concern:

Be it known that we, HENRY BERRY and KEYES A. HATHAWAY, citizens of the United States, residing at Birmingham, in the county of New Haven and State of Connecticut, have invented a new Design for Fruit or Cake Dishes; and we do declare the following to be a full, clear, and exact description of the invention, such as will enable others skilled in the art to which it appertains to make and use the same, reference being had to the accompanying drawing, and to letters or figures of reference marked thereon, which form a part of this specification.

15 The figure of the drawing is a representation of a perspective view of the dish.

The drawing represents a fruit or cake dish.

The bowl *a* and the base *b* are ornamented, the bowl *a* by producing on the surface a conventional imitation of alligator-skin. The 20 handle *c* may have any configuration desired.

What we claim as our invention, and desire to secure by Letters Patent, is—

The design for a fruit or cake dish having a surface ornamentation of the bowl in representation of alligator-skin, as shown and described.

In testimony whereof we affix our signatures in presence of two witnesses.

HENRY BERRY.

KEYES A. HATHAWAY.
